DESIGN FOR A FONT OF TYPE

Antonio C. Jiménez, Washington, D. C.

Application December 19, 1941, Serial No. 104,747

Term of patent 3½ years

To all whom it may concern:

Be it known that I, Antonio C. Jiménez, a citizen of Spain, residing at Washington, in the District of Columbia, have invented a new, original, and ornamental Design for Font of Type, of which the following is a specification, reference being had therein to the accompanying drawings, forming a part thereof, in which

Figs. 1 and 1a illustrate the upper case of the font of type showing the new design; and

Figs. 2 and 2a illustrate the lower case of the font of type.

The characteristic feature of my design resides in a font of type the characters of which have the specific configurations shown.

I claim:

The ornamental design for a font of type, substantially as shown and described.

ANTONIO C. JIMÉNEZ.
